UNITED STATES PATENT OFFICE

103,321

DESIGN FOR A MAGNETIC COMPASS

Walter E. Hull, Warren, Ohio

Application December 7, 1936, Serial No. 66,365

Term of patent 14 years

To all whom it may concern:

Be it known that I, Walter E. Hull, a citizen of the United States and a resident of Warren, in the county of Trumbull and State of Ohio, have invented a new, original, and ornamental Design for a Magnetic Compass, of which the following is a specification, reference being had to the accompanying drawing forming a part thereof, in which

Fig. 1 is a front view of a magnetic compass showing my new design;

Fig. 2 is a side view of the same; and
Fig. 3 is a top plan view of the same.

The direction indicia appearing on Fig. 1 are merely illustrative.

I claim:

The ornamental design for a magnetic compass substantially as shown and described.

WALTER E. HULL.
